UNITED STATES PATENT OFFICE.

JAMES FRED CREE, OF WATERFORD, NEW YORK, ASSIGNOR TO CLUETT, PEABODY & CO. INC., OF TROY, NEW YORK, A CORPORATION OF NEW YORK.

SOFT FOLD-COLLAR.

1,280,673.

Specification of Letters Patent.

Patented Oct. 8, 1918.

Application filed March 11, 1918. Serial No. 221,680.

To all whom it may concern:

Be it known that I, JAMES F. CREE, a citizen of the United States, residing at Waterford, county of Saratoga, and State of New York, have invented certain new and useful Improvements in Soft Fold-Collars, of which the following is a specification.

Reference may be had to the accompanying drawings, and the reference characters 10 marked thereon, which form a part of this specification. Similar characters refer to similar parts in the several figures therein.

This invention relates to fold-collars of various kinds, and is more particularly 15 adapted for soft fold-collars, wherein it is desirable to have the ends of the folded-over top of the collar held in close relationship to the band of the collar.

The principal object of the invention is to 20 provide a cheap and simple means whereby the ends of the folded-over top can be so held in close relationship to the band of the collar.

Other objects will appear in connection 25 with the following description.

Figure 1 of the drawings is a plan view of a soft fold-collar embodying my invention with the top of the collar opened out flat.

30 Fig. 2 is a view in elevation of a broken-away end-portion of the folded collar showing the inner side of the band.

Fig. 3 is a bottom plan view of the same.

Fig. 4 is a view in front elevation of a 35 broken-away end-portion of the collar, and a neighboring broken-away portion of a shirt, illustrating the manner in which the top-retaining loop on the first-buttoned end of the collar is attached to the front collar-button.

40 Fig. 5 is a similar view showing the neighboring end of the band buttoned upon said collar-button over said loop.

Fig. 6 is a similar view illustrating the 45 manner of attaching the loop on the other end of the collar to said collar-button.

Fig. 7 is a similar view showing the ends of the collar fully buttoned upon said collar-button.

50 Referring to the drawings wherein the invention is shown in preferred form, 1 is the band, and 2 the top of a collar. Both the top and the band may be made soft or not stiffly starched.

55 The band is provided with the usual end

buttonholes, 3 and 4, adapted to engage the front collar-button, 5, whereby said ends of the band are detachably secured to the neckband, 6, of a shirt, 7, in the usual manner.

The band may also be provided with the 60 usual back buttonhole, 8, or such other fastening means as may be desired.

The top is folded along its line of attachment to the band over upon the outer side 65 of the band in the usual manner.

In carrying out my invention, I attach by stitching, 9, to the inner side of the top near each end, one end of a tape-loop, 10, 10^a, the other end of which is insertible through an opening, 11, formed through the band 70 adjacent to the respective end buttonhole, 3 or 4.

This tape-loop, 10, is of such length that its other end is adapted to encircle a collar button inserted through said adjacent end 75 buttonhole.

In applying the collar, the loops, 10, 10^a, are inserted through the respective openings, 11, so that they project from the inner side of the band as shown in Figs. 2 and 3. The 80 loop on the first-buttoned end of the collar is then passed over the head of the front collar-button, 5, which projects from the neckband, 6, of the shirt in the manner illustrated in Fig. 4. The neighboring end of 85 the band is then buttoned upon said collar-button, 5, in the usual manner, as shown in Fig. 5.

The tape-loop, 10^a, on the last-buttoned end of the collar is then passed over the head 90 of said collar button, 5, as shown in Fig. 6, after which the last-buttoned end of the band is buttoned upon said collar button, 5, in the usual manner, with said last-buttoned end of the band inserted between the 95 band and the folded-over top at the other end of the collar, as shown in Fig. 7.

When the collar has been thus attached, the loops, 10, 10^a, serve as straps which hold the ends of the folded-over top in close engagement with the band of the collar. 100

For certain purposes of the invention, the form of the strap or loop is immaterial, so long as its end which is inserted through the opening in the band is adapted to engage the same collar button or fastening device which is engaged by the adjacent end buttonhole in the band.

105 By the means above described, I am able to avoid the use of buttons on the collar as 110

a means for holding the ends of the folded-over top in proper position with relation to the band, and the collar can be readily laundered, as the loops or straps, 10, 10^a, can be 5 made of launderable material.

As the tape-loops or straps are covered by the respective ends of the band, there is no visible evidence in use of the means whereby the ends of the folded-over top are held in 10 position.

What I claim as new and desire to secure by Letters Patent is—

1. A fold-collar having a band provided near its end with a buttonhole adapted to 15 engage a collar-button, and with an opening through the band adjacent to said button-hole; a folded-over top; and a strap attached to the inner side of the folded-over top near its end adjacent to said end of the band, said

strap being insertible through said opening 20 in the band and engageable with a collar-button inserted in said buttonhole in the band.

2. A fold-collar having a band provided near its end with a buttonhole adapted to engage 25 a collar-button, and with an opening through the band adjacent to said button-hole; a folded-over top; and a flexible loop attached to the inner side of the folded-over top near its end adjacent to said end of the 30 band, said loop being insertible through said opening in the band, and adapted to encircle a collar-button inserted in said buttonhole in the band.

In testimony whereof, I have hereunto 35 set my hand this 8th day of March, 1918.

JAMES FRED CREE.
